UNITED STATES PATENT OFFICE.

ARTHUR E. LEHMANN, OF ST. CHARLES, MISSOURI, ASSIGNEE, BY MESNE ASSIGNMENTS, TO COMMONWEALTH STEEL COMPANY, A CORPORATION OF NEW JERSEY.

COMBINED CAR END SILL AND END REINFORCING FRAME.

1,124,036.

Specification of Letters Patent.

Patented Jan. 5, 1915.

Application filed December 15, 1913. Serial No. 806,802.

To all whom it may concern:

Be it known that I, ARTHUR E. LEHMANN, a citizen of the United States, residing at St. Charles, Missouri; have invented a certain new and useful Improvement in Combined Car End Sills and End Reinforcing Frames, of which the following is a full, clear, and exact description, such as will enable others skilled in the art to which it appertains to make and use the same, reference being had to the accompanying drawings, forming part of this specification, in which, —

Figure 1 is an elevational view of a combined cast metal end sill and reinforcing end frame of my improved construction, the same being applied to the center and side sills of a car underframe. Fig. 2 is a horizontal section taken approximately on the line 2—2 of Fig. 1. Fig. 3 is a side elevational view of the combined end sill and end reinforcing frames.

My invention relates generally to railway car construction, and more particularly to a combined end sill and reinforcing end frame which is adapted to be applied to open end or wide vestibule cars.

The principal object of my invention is to provide a strong, and rigid structure which will materially reinforce the ends of cars, and which will effectually resist end shocks and crushing stresses, thereby reducing to a minimum the tendency of car bodies to telescope during collisions.

In order to materially strengthen and reinforce the end portions of cars, various metal structures have been devised and are at present in general use, which structures include metal underframes, platforms, buffering sills, one piece end frames, and reinforcing corner posts, and to further strengthen and reinforce the ends of cars, I propose to provide a sectional cast metal end sill and to form integral with certain of the sections thereof vertically disposed frames which combine with the end posts of the car superstructures, thereby forming an anti-telescopic shock absorbing and resisting structure, which materially reinforces and strengthens the ends of the car superstructure.

With the above and other objects in view my invention consists in certain novel features of construction and arrangement of

parts hereinafter more fully described and claimed.

In the accompanying drawings, I have shown the center sills of the underframe of the built-up type, but it will be readily understood that said center sills may be made in one piece. Each of the center sills as shown, comprises a vertically disposed web plate 1, provided at its upper end with a pair of oppositely arranged angles 2, and at its lower end with a single angle 3. The upper ends of the sills thus constructed are united by a longitudinally extending top plate 4.

The side sills 5, as shown, are of Z-shape in cross section, but said sills may be of any desired cross sectional shape, and the combined end sill and end reinforcing frames contemplated by my invention are each composed of a horizontally disposed channel shape member 6, which is substantially channel-shape in cross section, and formed integral with the outer end of this sill member is a post or upright 7 to which the lower portion of the corner 7^a of the car body is fixed.

Formed integral with the sill member near its inner end is a vertically disposed post or upright 8 to which the lower end of the corresponding one of the door posts 8^a is fixed. The upper ends of the posts 7 and 8 are united by a horizontally disposed rail 9, and formed integral therewith and with the central portion of the sill member 6 is an intermediate post or upright 10. Formed integral with the central portion of the rail 9 and forming an extension of the upright 10 is an upwardly projecting bracket 11, to which is fixed the lower end of one of the car end posts 11^a.

Formed integral with the outer end of the sill member 6 and with the post or upright 7 is a vertically disposed plate 12 preferably formed with a marginal flange 13, said plate occupying a position at right angles to the sill member 6 so that its lower end bears directly upon the end portion of the corresponding side sill 5. The lower end of this plate or bracket is rigidly fixed to the side sill by means of rivets or in any suitable manner.

A pair of the sill members 6 with their reinforcing frames are applied to the center and side sills of a car underframe in trans-

verse alinement with each other, the inner end of said sill members being fixed to the center sills in any suitable manner, and arranged between the center sills in alinement with said sill members 6, is a cast metal spacing block 14 preferably provided with a marginal flange, and said spacing block is rigidly fixed to the adjacent portions of the sills and to the inner ends of the sill members 6 in any suitable manner.

10 An upper tie plate 15 overlies the center sills and the inner end portions of the sill members 6, said tie plate being fixed to said center sills and sill members in any suitable manner, and a corresponding bottom tie plate 16 is applied to the underside of the spacing block 14 and to the inner ends of the sill members 6, said bottom tie plate being fixed to these parts in any suitable manner.

15 20 As shown in the drawings, the web plates 1 of the center sills are slotted or perforated to accommodate the bottom tie plate 16, but if desired, the members 6 and 14 may be formed of equal depth with the center sills and where such construction is carried out, the bottom tie plate extends beneath the center sills as shown by dotted lines in Fig. 1. Formed on or fixed to the outer faces of the vertical walls of the sill members 6 are 25 lugs or brackets 17 to which are fixed the inner ends of horizontally disposed rails 18 which latter form a support for the upper ends of the side steps leading down from the platform. (See Fig. 1.)

30 35 In the drawings I have shown two center sills or a center sill of the girder type having two vertically disposed members, but it will be readily understood that the transverse sill members 6 may be combined with a single center sill, that is, a center sill having but a single vertical web or member. The sill members 6 and the spacing block 14 provide a strong and substantial end sill for the car underframe, and the upright 40 45 skeleton frames which are formed integral with the sill members 10 to the sides of the end door wall materially reinforce the end portion of the car and resist end shocks and crushing strains, such as the car may be subjected to in case of collision.

50 The upright skeleton frames combine with the door, corner and end frame posts of the superstructure, and thus form a strong rigid end construction which is antitelescopic in effect. The upright plates or brackets at the ends of the skeleton frames have substantial bearing on the end portions of the side sills of the underframe, thus materially assisting the skeleton frames in reinforcing 55 60 the end portion of the car.

65 In case my improved reinforcement is applied to cars which do not require an end door opening, the uprights or posts 8 may be united by transversely disposed rails such as 19 shown by dotted lines in Fig. 1.

70 It will be readily understood that minor changes in the size, form and construction of the various parts of my improved end sill and reinforcing end frames can be made and substituted for those herein shown and described, without departing from the spirit of my invention, the scope of which is set forth in the appended claims.

I claim:

1. A reinforcing structure for car ends, 75 comprising a sectional sill, and upright frames formed integral with certain sections of said sill.

2. A reinforcing structure for car ends, comprising a sectional sill, upright frames 80 formed integral with certain of the sections of said sill, and side sill engaging brackets integral with said upright frames.

3. A car end reinforcing structure, comprising a pair of sill members arranged between the center sill and side sills of the underframe, and upright frames integral with 85 said sill members.

4. A car end reinforcing structure, comprising a pair of sill members arranged between the center sill and side sills of the underframe, upright frames integral with said sill members, and side sill engaging brackets integral with the upright frames.

5. A car end reinforcing structure, comprising an end sill member and a series of upright members integral with said end sill member, which upright members are adapted to engage and be fixed to the door, end wall and corner posts of the car end structure.

6. A car end reinforcing structure, comprising an end sill member, a series of upright members integral with said end sill member, which upright members are adapted to engage and be fixed to the door, end wall and corner posts of the car end structure, and a side sill engaging bracket integral with the upright which engages the corner post.

7. The combination with a car underframe center sill and side sills, of end sill members arranged between said center and side sills, and skeleton frames integral with said end sill members, which skeleton frames are adapted to engage and reinforce the lower portion of the car end structure.

8. The combination with a railway car underframe center sills and side sills, of end sill members arranged between the center sills and side sills, skeleton frames integral with and extending upwardly from said end sill members for reinforcing the car end structure.

9. The combination with a railway car 125 underframe center sills and side sills, of end sill members arranged between the center sills and side sills, skeleton frames integral with and extending upwardly from said end sill members for reinforcing the car end 130

structure, and a spacing block positioned between the center sills substantially in alignment with the end sill members.

10. The combination with a railway car underframe center sills and side sills, of end sill members arranged between the center sills and side sills, skeleton frames integral with and extending upwardly from said end sill members for reinforcing the car end structure, a spacing block positioned between the center sills substantially in alignment with the end sill members, and tie plates uniting the inner ends of the end sill members and the spacing block.

15. 11. The combination with a railway car underframe center sills and side sills, of end sill members arranged between the center sills and side sills, skeleton frames integral with and extending upwardly from said end sill members for reinforcing the car end structure, a spacing block positioned between the center sills substantially in alignment with the end sill members, and a tie plate uniting the inner ends of the end sill members and overlying the center sills.

12. The combination with a railway car underframe center sills and side sills, of end sill members arranged between the center sills and side sills, skeleton frames integral with and extending upwardly from said end sill members for reinforcing the car end structure, a spacing block positioned between the center sills substantially in alignment with the end sill members, and a tie plate arranged beneath and uniting the inner ends of the end sill members.

35. 13. The combination with a car center sill and side sills, of a sectional end sill attached to and arranged between the center sill and

side sills, and reinforcing frames integral ⁴⁰ with and extending upwardly from said sectional end sill.

14. In car construction, an end sill formed in two main parts which are adapted to be positioned between the underframe ⁴⁵ center sill and side sills, and car end reinforcing members integral with and extending upwardly from said end sill members.

15. In railway car construction a reinforcing structure comprising an end sill ⁵⁰ member adapted to be positioned between and fixed to the center and side sills of the car underframe, and a side sill engaging bracket integral with said end sill member.

16. In railway car construction, a reinforcing structure comprising a sill member, one end of which is adapted to be rigidly fixed to the center sill of a car underframe, a corner post integral with said sill member, and a side sill engaging bracket integral ⁵⁵ ⁶⁰ with said corner post and the outer end of said sill member.

17. As a new article of manufacture, a cast metal reinforcing structure for car ends comprising a sill member, the inner end of ⁶⁵ which is adapted to be rigidly fixed to the center sill of a car underframe, an upright integral with the outer end of said sill member, and a side sill engaging bracket integral ⁷⁰ with said upright.

In testimony whereof I hereunto affix my signature in the presence of two witnesses, this 5th day of December, 1913.

ARTHUR E. LEHMANN.
